(57) **CLAIM**

We claim the ornamental design of an animated graphical user interface for a display screen or portion thereof, as shown and described.

DESCRIPTION

The present application is related to U.S. application Ser. No. 14/147,010, filed on Jan. 3, 2014.

FIG. 1 is a detailed view according to an embodiment of an animated graphical user interface for a display screen or portion thereof.

FIG. 2 is a detailed view according to an embodiment of an animated graphical user interface for a display screen or portion thereof.

FIG. 3 is a detailed view according to an embodiment of an animated graphical user interface for a display screen or portion thereof.

FIG. 4 is a detailed view according to an embodiment of an animated graphical user interface for a display screen or portion thereof.

FIG. 5 is a detailed view according to an embodiment of an animated graphical user interface for a display screen or portion thereof; and,

FIG. 6 is a detailed view according to an embodiment of an animated graphical user interface for a display screen or portion thereof.

The broken line(s) on the display screen and text form no part of the claimed design. The appearance of images sequentially transitions between the images shown in FIGS. 1-6. The process or period in which one image transitions to another forms no part of the claimed design.
